FIG. 1

FIG. 2

FIG. 3

FIG. 4

FIG. 5

FIG. 6

FIG. 7

FIG. 1 is a right front perspective view of a sport shoe showing my new design;

FIG. 2 is a front elevational view thereof;

FIG. 3 is a left side elevational view thereof;

FIG. 4 is a top plan view thereof;

FIG. 5 is a rear elevational view thereof;

FIG. 6 is a partial left side elevational view of another embodiment of my new design of FIG. 1 wherein an extra stitchline has been applied around the throat of the shoe;

FIG. 7 is a partial left side elevational view of yet another embodiment of my new design of FIG. 1 wherein two, spaced apart, chevrons of contrasting color to the upper have been substituted for the chevrons of the FIG. 1 design.

The bottom of the shoe is plain and unornamented.

I claim:

The ornamental design for a sport shoe, as shown and described.
